Patented Oct. 2, 1917.

AUGUST FONTAINE

884 Watson E. Coleman

Attorney

UNITED STATES PATENT OFFICE.

AUGUST FONTAINE, OF GREEN BAY, WISCONSIN.

PULLEY ATTACHMENT.

1,241,726.

Specification of Letters Patent.

Patented Oct. 2, 1917.

Application filed March 31, 1917. Serial No. 158,928.

To all whom it may concern:

Be it known that I, AUGUST FONTAINE, a citizen of the United States, residing at Green Bay, in the county of Brown and State of Wisconsin, have invented certain new and useful Improvements in Pulley Attachments, of which the following is a specification, reference being had to the accompanying drawings.

10 This invention relates to certain improvements in pulley attachments and it is an object of the invention to provide a novel and improved device of this general character adapted to be applied to a drive pulley or 15 the like for increasing the radial diameter thereof in order to vary the peripheral speed of said pulley without the necessity of adjusting the speed of the motor.

The invention consists in the details of 20 construction and in the combination and arrangement of the several parts of my improved pulley attachment whereby certain important advantages are attained and the device is rendered simpler, less expensive 25 and otherwise more convenient and advantageous for use, all as will be hereinafter more fully set forth.

The novel features of the invention will 30 hereinafter be definitely claimed.

35 In order that my invention may be the better understood, I will now proceed to describe the same with reference to the accompanying drawings, wherein—

Figure 1 is a view partly in elevation and 40 partly in section illustrating a pulley attachment constructed in accordance with an embodiment of my invention and in applied position;

Fig. 2 is a fragmentary circumferential 45 sectional view taken through my improved attachment as herein disclosed;

Fig. 3 is a sectional view taken substantially on the line 3—3 of Fig. 1; and

Fig. 4 is a fragmentary view in elevation 50 of one of the blocks as herein embodied.

As disclosed in the accompanying drawings, P denotes a pulley of ordinary or preferred construction and R denotes my improved attachment which is in the nature of a supplemental rim and adapted to be disposed circumferentially around the rim 55 of the pulley P.

As herein embodied, my attachment R comprises a plurality of blocks 1 of a length substantially equal to the width of the rim of the pulley P and having their adjacent

faces disposed on a predetermined bevel so that the attachment may assume a substantially circular or cylindrical form.

The blocks 1 adjacent their opposite ends 60 are provided with the transversely disposed openings 2 through which are loosely directed the flexible members 3 preferably of wire. The end portions of said members 3 are disposed through the openings in two 65 of the adjacent blocks 1 and terminate in the hooks 4 engageable with the outer faces of said two last named blocks whereby it will be perceived that as said blocks are separated the flexible members or wires 3 will 70 be so moved as to tighten the blocks 1 and cause the same to snugly fit upon the pulley P.

In order to separate the two blocks 1 with which the free end portions of the flexible 75 member 3 coact, I provide the wedge member 5 adapted to be inserted between these two blocks and the under surface of the wedge member 5 is provided with the transversely disposed grooves or channels 6 80 adapted to receive the overlying portions of the flexible members 3 for a purpose which is believed to be self-evident.

I also find it of advantage to provide the wedge member 5 with the radially disposed 85 openings 7 adapted to register with the openings 8 formed in the rim of the pulley P. Through said registering openings 7 and 8 are adapted to be directed the bolts 9 with the heads 10 thereof outwardly directed.

Coacting with the free ends of the bolts 9 are the nuts 11 of a conventional type and which are adapted to engage the inner face of the rim of the pulley P. By this arrangement 95 it will be perceived that my improved attachment is effectively held to the pulley P yet capable of convenient removal. It is also to be observed that the outer portions of the openings 7 are counter-sunk or 100 reamed so that the heads 10 of the bolts 9 will be disposed below the periphery of the attachment and therefore afford no obstruction or interference with the belt which may be directed around the attachment.

When it is desired to displace my improved attachment it is only necessary to remove the wedge member 5 and to force the adjacent blocks 1 one toward the other, which will permit an expansion of the attachment.

From the foregoing description, it is

thought to be obvious that a pulley attachment constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. An attachment for a pulley adapted to be disposed circumferentially therearound and comprising a plurality of separable blocks, a flexible member loosely directed through said blocks and having its extremities disposed through two adjacent blocks with one extremity interlocking with one of said blocks and its opposite extremity interlocking with the second of the blocks, and a wedge member insertible between said two last named blocks.
2. An attachment for a pulley adapted

to be disposed circumferentially therearound and comprising a plurality of separable blocks, a flexible member loosely directed through said blocks and having its extremities disposed through two adjacent blocks with one extremity interlocking with one of said blocks and its opposite extremity interlocking with the second of the blocks, and means for securing the attachment to the pulley.

3. An attachment for a pulley adapted to be disposed circumferentially therearound and comprising a plurality of separable blocks, a flexible member loosely directed through said blocks and having its extremities disposed through two adjacent blocks with one extremity interlocking with one of said blocks and its opposite extremity interlocking with the second of the blocks, a wedge member insertible between said two last named blocks, and means coacting with the wedge member for securing the attachment to the pulley.

In testimony whereof I hereunto affix my signature in the presence of two witnesses.

AUGUST FONTAINE.

Witnesses:

JOSEPHINE A. KITTNER,
ERL GREENWOOD.
